UNITED STATES PATENT OFFICE.

JOSEPH GOULDBOURN, OF LEICESTER, ENGLAND, ASSIGNOR TO UNITED SHOE MACHINERY CORPORATION, OF PATERSON, NEW JERSEY, A CORPORATION OF NEW JERSEY.

ABRADING MACHINE.

Application filed December 15, 1922, Serial No. 607,198, and in Great Britain January 23, 1922.

This invention relates to abrading machines and is herein illustrated as embodied in a machine designed for grinding blades of rotary cutters adapted for use in heel trimming machines, although in various aspects the invention is not limited to embodiment in abrading machines of the illustrated type or to use in grinding heel trimming cutters, but may be embodied in analogous organizations and be useful for similar abrading operations.

Rotary cutters of the type customarily employed in machines for trimming the peripheries of heels are each provided with a plurality of longitudinally curved blades having surface and cutting edge profiles determined by the heel contours it is desired to produce. In order that such cutters shall perform trimming operations properly, it is essential that all the blades of a given cutter be ground so that their cutting edges shall have exactly the same bevel and profile.

The blades of rotary cutters of the above-described type are generally ground by hand and the skill of the workman is depended upon to impart to the cutting edges of the blades the same curvature as well as the same bevel thereof. It is obvious that this is a slow process and that even an expert who is able to grind one such blade with fair accuracy by manual control cannot take a second blade and grind it like the first. On the other hand, when a machine is relied upon to perform the operation indicated above, it is essential that provision be made for readily presenting all the blades of the rotary cutter in the same position or in like positions relatively to the grinding element, and in relatively moving the grinder and the blades through the same or like paths in order that the same cutting edge bevel and curvature be imparted to the various blades.

Accordingly, it is an object of this invention to provide an improved organization for grinding the blades of a rotary cutter in such a manner as to produce upon all of the blades the same predetermined edge bevel and curvature, without in any respect depending upon the skill of the operative in determining the cutting edges imparted to the various blades.

A feature of the invention consists in the provision of means for supporting a plurality of cutting blades constructed and ar-

ranged to present the blades to an abrading element in such a manner that like cutting edges will be imparted to all of the blades. In the illustrated embodiment of the invention there is provided a grinding wheel and a plurality of blade carriers for receiving a plurality of blades and presenting the blades in the same relation to the grinding wheel at different portions of its periphery. As illustrated movement of one of the two blade carriers is transmitted to the other blade carrier by means of connections extending between them.

In accordance with another feature of the invention, the illustrated abrading machine is adapted to operate simultaneously upon a plurality of longitudinally curved cutting blades and to impart to all of them like cutting edges having predetermined edge bevels and profiles. As illustrated the blade carriers are mounted to rock about an axis extending parallel to the axis of the grinding wheel and all of the blades are supported so that their centers of curvature coincide with the axis of the grinding wheel. By virtue of this arrangement the blade carrier and supported blade may be rocked, or fed, toward or away from the periphery of the grinding wheel without any change resulting in the angle of bevel produced by the grinding operation.

These and other features and advantages of the invention will appear from a consideration of the following specification and accompanying drawings in which:

Figure 1 is a side elevation of the machine, with a cover plate thereof removed, showing the parts in operative position;

Fig. 2 is a front elevation of the machine partly in section;

Fig. 3 is a sectional plan view of a cutter holding mechanism of the machine; and

Fig. 4 is a sectional elevation on the line 4-4 of Fig. 3.

The machine comprises a vertical column 1 having at its upper end bearings 2, 2 for a horizontal shaft 3 having fixed on one end of it a rotary grinding wheel 4. The shaft also has fixed on it between the bearings 2, 2 a pulley 5 which is driven by a belt from a suitable source of power.

Fixed on the front of the column 1 is a bracket 7 which has formed on it a forwardly and downwardly inclined slideway 8 on which is slidably mounted a slide 9. 110

The slide 9 may be adjusted along the slide-way 8 by means of a screw 10 which is rotatably mounted in a bearing 11 on the slide 9 and which is threaded through a lug 12 formed on the bracket 7. The screw 10 is prevented from moving lengthwise by an attached collar 13 and a hand-wheel 14 engaging opposite ends of the bearing 11, the hand-wheel providing means by which the screw may be rotated.

The slide 9 has formed on it a bearing 15 in which is rotatably and slidably mounted a shaft 16 parallel to the grinding wheel shaft 3. The bearing 15 is so arranged on the slide 9 that when the slide is adjusted along the inclined slideway 8 the shaft 16 is moved radially of the grinding wheel shaft 3. The shaft 16 has at its right hand end (Fig. 2) a blade holding mechanism, herein-after described in detail, and at its left hand end passes through a slot 17 (radial to the axis of a shaft 30 hereinafter described) formed in a casing 18 and is reduced at 19 to receive a block 20 which is guided in a groove 21, parallel to the slot 17, formed in a cover plate 22 fixed to the casing 18. The shaft has fixed near its left hand end a gear segment 23 which is fastened to the shaft by means of two screws 24, 25, passing through the hub of the segment and engaging flat faces on the shaft. The segment may be adjusted about the shaft by slackening one of the screws and tightening the other.

The slide 9 has projecting upwardly from it a lug 26 in which is fixed, by a screw 27, a shaft 28 on which is rockably mounted a bearing member or support 29 bifurcated at its lower end to embrace the lug 26. The member 29 has at its upper end a horizontal bearing in which is slidably and rotatably mounted a shaft 30 which is parallel to the shaft 16 and to the grinding wheel shaft 3. One end of the bearing on the member 29 is reduced at 31 to provide a bearing for the upper end of a long link 32 the lower end of which is pivotally mounted on a stud 33 fixed in the bracket 7. The link 32 thus provides a support for the upper end of the bearing member 29 and guides this end of the member about the axis of the stud 33 when the slide 9 is adjusted along the inclined slideway 8. The shaft 30 has at its right-hand end (Fig. 2) a blade holding mechanism similar to the blade holding mechanism on the right-hand end of the shaft 16 and at its left-hand end has pivotally mounted on it the casing 18 and cover-plate 22 above referred to. Fixed on the left-hand end of the shaft 30, by a taper pin 34, is a second gear segment 35. The gear segments 23, 35 are operatively connected by a rack 36 slidably mounted in the casing 18 and held up to the segments by a bar 37 supported by screws 38, 39 threaded through the casing 18 and locked in adjusted position

by nuts 39, 39. Fixed to the gear segment 35 is a segmental plate 40 which is positioned between two segmental plates 41, 41 fixed to the gear segment 23 so that if either of the shafts 16, 30 is moved endwise in its bearing the other shaft will move endwise also. It will be noted that if either of the shafts is rocked in its bearing, the other shaft will, by reason of the rack and gear segments, be similarly rocked. The two shafts 16, 30 together with their associated blade holders constitute sliding and rocking blade carriers.

The blade holding mechanisms are similar and each comprises an arm 42 projecting from the shaft 16 or 30. Projecting from the arm 42 is a block or casing 43 in which is formed a slotted guideway 44 for a slide 45. The slide is adjusted along the guideway 44 by a screw 46 rotatably mounted in a cap 47 fixed on the block or casing 43, which screw may be rotated by a hand wheel 48. The blade 49 to be ground is clamped between the slide 45 and a block 50 fixed by a bolt 51 to the arm 42. The slide 45 and block 50 each have formed on them a curved rib 52 to enter the usual grooves in the opposite sides of the blade 49. The ribs are concentric with the axis of the shaft 16 or 30 and are of the same radius of curvature as the grooves in the blades so that when the blade carriers are swung about the bearings of their respective shafts, the blades are swung towards or away from the grinding wheel about their respective axes. Hence each blade can be fed in a curved path corresponding to its own lengthwise curvature, thereby maintaining the edge bevel constant as the blade wears away in consequence of repeated grindings. The longitudinal shape of the blade edge is also controlled by the swinging of the blade carrier around its axis as the blade is traversed across the wheel in consequence of sliding movement of the blade carrier.

To prevent dust from getting into the guideway 44 or on to the screw 46, a thin metal strip 53 has its ends fastened to the slide 45 and passes around a semi-circular portion of the cap 47 at one end of the block 43 or casing 43 and around a semi-circular block 60 at the other end of the block or casing 43 so that the opening in the block through which the slide 45 projects is always covered by the strip. To prevent dust from getting into the bearings of the shafts 16 and 30 expandable protectors 54, 54 surrounding the shafts are fixed at one end to the arms 42 and at the other end to the bearings of the shafts. The protectors comprise leather washers stitched together at their inner and outer edges, as shown in Fig. 3.

In the operation of the machine, blades 49 are placed between the blocks 50 and slides 45, with their rear end faces posi-

tioned against stop pins 55 fixed in the slides 45 and the blades are then clamped by means of the screws 46. At this time the lower end of the rack bar 36 will be resting 5 against a stop screw 56 fixed in the casing 18. If the slide 9 has been correctly adjusted, all the operator then has to do is to grasp one of the blade holders or any convenient part of the block or casing 10 43 and swing it about the axis of its shaft to bring the blade into engagement with the grinding wheel and move it to and fro axially of its shaft to traverse it past the grinding wheel which is of a width but a 15 small fraction of the width of the edge to be ground. The other blade then automatically receives similar movements about the axis of its shaft (through the gear segments 23, 35 and rack 36) and past the grinding 20 wheel (through the segmental plates 40, 41).

The contour of the edge formed by the ground face and the outer face of the blade is entirely determined by the movements towards and from the periphery of the 25 wheel which the operator gives to the particular one of the blade holders he is holding as he traverses that blade holder to and fro across the wheel. Whatever contour he gives to the one blade is faithfully reproduced on the other blade by reason of the gear segment and rack connection and the plate coupling 40, 41. The aspect of the ground face of the blade relatively to the body of the latter is evidently dependent 30 upon the position of the axis of the shaft 16 or 30, as the case may be, relatively to the wheel axis and is obviously identical for both blades so long as the axes of both the shafts 16 and 30 are equidistant from the wheel axis and this is assured by the 35 link 32 and associated parts as more fully described hereinafter. The weight of the blade holding mechanisms is balanced by a spring 57 attached at one end to a hook 40 58 fixed to the gear segment 35 and at the other end to a bolt 59 adjustably mounted in the casing 18.

The bearing member 29 and link 32 are so arranged and proportioned that when 50 the slide 9 is adjusted along the inclined guideway 8, and moves the shaft 16 radially of the grinding wheel (either to compensate for reduction in diameter of the grinding wheel due to wear, or to alter the angle or 55 aspect of the ground face of the blade in relation to the body of the blade), the radial distances of the shafts 16, 30 from the grinding wheel shaft remain substantially equal. The angle subtended by a line joining the axis of the shaft 3 with the axis of 60 the shaft 30 and a line joining this latter axis and the pin 55 of the upper carrier, all as seen in Figure 1, is at all times equal to the corresponding angle at the axis of the shaft 16. This latter condition insures that

the two blades, when their faces are fully ground to the same aspect, are also of identical length, assuming of course that they have both been properly set up to the pins 55, and are therefore sufficiently identical to be 70 used in the high speed trimming machine without disturbing the balance thereof. The arrangement and proportioning of the parts 75 29 and 32, above referred to, to secure the results stated, causes a movement of the axis of the shaft 30 having components both radially of the wheel axis and peripherally of the wheel. The peripheral component is compensated for by the rack connection which effects an appropriate relative rotary 80 movement of the blade carriers.

Although the invention has been described by reference to a specific machine, it should be understood that, in its broader aspects, the invention is not limited to the machine 85 selected for illustration.

Having described my invention, what I claim as new and desire to secure by Letters Patent of the United States is:—

1. In a machine for simultaneously grinding a pair of curved blades, a grinding wheel, a blade carrier for rocking a curved blade to be ground about its axis of curvature to present it in a predetermined relation to the periphery of the wheel, and a 90 second blade carrier for rocking a like blade about its axis of curvature to present it in the same relation to the wheel at a different part of its periphery.

2. In a machine for simultaneously grinding a pair of curved blades, a grinding wheel, a blade carrier for rocking a curved blade to be ground about its axis of curvature to present it in a predetermined relation to the periphery of the wheel, and a 100 second blade carrier for rocking a like blade about its axis of curvature to present it in the same relation to the wheel at a different part of its periphery, and connections between said blade carriers for causing movement of one blade holder to be transmitted to the other.

3. In a machine for grinding a pair of blades, a grinding wheel, a blade clamping carrier slidable on an axis parallel to the axis of the wheel to carry the edge of a blade to be ground across the periphery of the wheel, and a second blade clamping carrier slidable on an axis parallel to the axis of the 115 wheel to carry a like blade edge across the wheel at a different station on the periphery of said wheel.

4. In a machine for grinding a pair of curved blades, a grinding wheel, a blade carrier having a rock shaft, means for holding a curved blade on the carrier in coaxial relation to said shaft, a second blade carrier having a rock shaft parallel to the first rock shaft, means for holding a blade like the first on said second carrier, and means con- 120 125 130

- necting said blade carriers to transmit rocking movement of one carrier to the other.
5. In a machine for grinding a pair of curved blades, a grinding wheel, a pair of shafts mounted to slide and rock on parallel axes, blade clamping holders carried by the shafts for holding a pair of curved blades, means for causing simultaneous sliding of said shafts to carry the blade edges across the grinding wheel, and means for causing simultaneous rocking of said shafts to impart the same shape to both blade edges.
6. In a machine of the character described, a grinding member, a blade carrier mounted to slide and rock on an axis parallel to the axis of the wheel, means for holding a curved blade on the carrier with its center of curvature at said rocking axis, and means for rocking said blade carrier on said axis to control the longitudinal shape of the edge of the blade and maintain the bevel constant.
7. In a machine of the character described, a grinding wheel, a shaft mounted to slide and rock on an axis parallel to the axis of the wheel, and a blade holder carried by the shaft for holding a curved blade with its center of curvature at the axis of the shaft.
8. In a machine of the character described, a grinding wheel, a shaft mounted to slide and rock on an axis near the periphery of the grinding wheel, yielding means tending to rock the shaft in one direction, an arm fixed to the shaft, a fixed clamp member on the arm to engage one side of a blade and a movable clamp member to engage the other side of the blade.
9. In a machine of the character described, a grinding wheel, a fixed clamp member, a casing, a movable clamp member projecting through a slot in the casing, means extending into the casing for moving said movable clamp member, and a flexible member attached to said movable clamp member and covering said slot.
10. In a machine for grinding trimming blades in pairs, a grinder, a pair of blade carriers, each comprising a slideable rock shaft, and interengaging plates on the shafts for transmitting sliding movement of one shaft to the other without interfering with rocking movement.
11. In a machine for grinding trimming curved blades in pairs, a grinder, a pair of rock shafts, means on each rock shaft for holding a curved blade with its center of curvature at the axis of the shaft, and connections between the shafts comprising toothed members for transmitting rocking movement of one shaft to the other.
12. In a machine for grinding trimming blades in pairs, a grinder, a pair of blade carriers, each comprising a rock shaft, a gear segment fixed to each shaft, and a rack engaging said gear segments to transmit rocking movement from one shaft to the other.
13. In a machine for grinding trimming blades in pairs, a grinder, a pair of blade carriers, each comprising a slideable rock shaft, toothed members connecting said shafts to transmit rocking movement of one shaft to the other, and interengaging plates for transmitting sliding movement from one shaft to the other without interfering with said rocking movement.
14. In a machine for grinding trimming blades in pairs, a grinding wheel, a pair of rocking blade holders stationed at different points spaced about the periphery of the wheel, connections for causing the holders to maintain the same relation to the periphery of the wheel, and pins on the blade holders for engaging the rear ends of the blades to position the edges to be ground in the same relation to the wheel.
15. In a machine for grinding blades in pairs, a grinding wheel, a pair of parallel bearings, shafts slideable and rockable in said bearings, blade holders at one end of said shafts, a casing enclosing the other end of the shafts, and connections in the casing between said shafts for causing both sliding and rocking movements of one shaft to be transmitted to the other.
16. In a machine of the character described, a grinding wheel, a plurality of blade holders positioned in the same relation to the periphery of the grinding wheel at different stations, and means for simultaneously adjusting the blade holders towards the axis of the wheel and maintaining said holders in the same relation to the periphery of the wheel as the wheel wears away.
17. In a machine of the character described, a grinding wheel, a plurality of blade holders positioned in the same relation to the periphery of the grinding wheel at different stations, rock shafts for said blade holders, means operable by movement of a single member for adjusting said rock shafts towards the axis of the grinding wheel, and means for causing a relative rocking movement of said blade holders in consequence of said adjustment to maintain the work in the same relation to the wheel.
18. In a machine of the character described, a grinding wheel, a frame, a pair of blade holders positioned in the same relation to the periphery of the grinding wheel at different stations, rock shafts for said blade holders, a slide for adjusting one of said rock shafts towards the axis of the grinding wheel, a link and a bearing member connecting the other rock shaft with the slide and the frame to control the movement of said shaft, and means for causing a relative movement of said blade holders during said adjusting movement to maintain the work in the same relation to the wheel.
19. In a machine of the character de-

scribed, a grinding wheel, a pair of blade holders positioned in the same relation to the periphery of the grinding wheel at different stations, rock shafts for said blade holders, means for adjusting said rock shafts towards the axis of the wheel, and rack and gear connections between said rock shafts for causing a relative rocking movement of the blade holders as the shafts approach one another in consequence of their adjustment to maintain the work in the same relation to the wheel.

20. In a machine of the character described, a frame, a grinding wheel, a slide movable towards and from the axis of the wheel, a blade carrier having a rock shaft journaled in said slide, a bearing member pivoted to said slide, a second blade carrier

having a rock shaft journaled in said bearing member, and a link pivotally connecting 20 said rock shaft with the frame.

21. In a machine for grinding trimming blades, a blade carrier comprising a body member having an elongated opening therein, an arm rigidly secured to the body member, a second arm extending outwardly from the body member and mounted for adjustment throughout the length of the elongated opening therein, and a closure constructed and arranged constantly to cover 25 the opening notwithstanding adjustments of the second arm throughout the length of the opening.

In testimony whereof I have signed my name to this specification.

JOSEPH GOULBOURN.
